(57) **CLAIM**

The ornamental design for a tube light, as shown and described.

DESCRIPTION

FIG. 1 is a front perspective view of a tube light showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a portion of the perspective view of FIG. 1 enlarged for magnification purposes;

FIG. 10 is a portion of the perspective view of FIG. 2 enlarged for magnification purposes;

FIG. 11 is a top plan view of FIG. 7 enlarged for magnification purposes; and,

FIG. 12 is a bottom plan view of FIG. 8 enlarged for magnification purposes.

In FIGS. 1-6, portions of the design are broken by a pair of break lines. The broken away symbols in the drawings indicate that the appearance of any portion of the article between the pair of break lines forms no part of the claimed design.
